UNITED STATES PATENT OFFICE.

WALTER J. FROST, OF KENOSHA, WISCONSIN, ASSIGNOR TO THE FROST MANUFACTURING COMPANY, OF KENOSHA, WISCONSIN, A CORPORATION OF WISCONSIN.

ADJUSTABLE FLANGE ON OVERFLOW CONNECTION FOR DRAINS.

Application filed January 25, 1926. Serial No. 33,528.

This invention relates to improvements in adjustable flanges for overflow connections for drains, and refers more particularly to a flange adjustably mounted with relation to the overflow connection, which latter is adapted for use with waste and overflow connections for bath tubs, sinks, and the like.

In the specific embodiment of the present invention, a flange is adjustably mounted between the overflow connection and the wall of the bath tub or sink, for the purpose of compensating for the difference in degrees of slope of various types of bath tubs.

Many objects and advantages will be hereinafter brought out.

In the drawings,

Figure 1 is a fragmentary front view of the overflow drain;

Figure 2 is a cross-sectional view taken on line 2—2 of Figure 1;

Figure 3 is a cross-sectional view through a bath tub showing the complete assembly of overflow connection and bottom drain; and

Figure 4 is a perspective view of one form of flange;

Figure 5 is a cross-sectional view similar to Figure 2, showing a flexible seat on the overflow connection against which the adjustable flange abuts.

Referring more in detail to the drawings, 1 designates the bottom, and 2 the side wall of a bath tub. The side walls of bath tubs 35 vary from 3 to 10 degrees in slope. The overflow pipe 3 must always remain in vertical position. Therefore, some means must be provided to compensate for the difference in slope. The present invention is particularly designed to accomplish this purpose, as 40 will be hereinafter particularly described.

The overflow pipe 3 has an enlarged head 4 commonly known as a top elbow, the lower end of said pipe being connected with the 45 T 5 which has the extension 6, and to which T is connected the drain 7 from the bottom 1 of the bath tub.

As one of the features of the present invention, the outer end of said enlarged head 50 4 is so made as to have an open face into which is adapted to be inserted the adjustable flange referred to as a whole as 8. This adjustable flange, as more particularly illustrated in Figure 4, comprises a flat annular 55 ring 9 of substantial width having on one

edge the annular flange 10. An upwardly tapered portion 11 connects with the flat portion 9, said upwardly tapered portion terminating in the flange 12. As shown clearly in Figure 2, the curved surface 11 is adapted to seat on the edges of the open face of the elbow 4, the flange 12 preventing excess movement and forming a pouring lip to direct the overflow into the pipe 3. The flange 10 is utilized in the present invention to 60 retain in place the flexible washer 13 against the side wall 2 of the bath tub. The side wall, of course, is apertured as shown at 14, and a perforated drain plate 15 is mounted in front thereof. This perforated plate 15 is held in position by means of the bolt 16 screwed into the stud 17. In assembling the device, the overflow pipe 3 may have the top elbow fixedly attached thereto. This assembly may be cast, in which event a cross-bar having a screw threaded aperture may be cast integral with the cast elbow, or said elbow may be made of sheet metal drawn or wrought to shape, in which event the screw threaded stud 17 for the reception of the 65 bolt 16 may be set in and soldered or secured in any other desirable way. The flange 8 is then positioned in the open face of the elbow 4 and the flexible washer 13 inserted and held in place by the flange 10, if said washer is used. This assembly is then positioned against the side wall 2 of the bath tub in such manner that the overflow pipe 3 will be positioned in an absolute vertical plane, the flange 8 being movable to compensate for 70 the slope of the said side wall 2. The perforated overflow plate 15 is then placed over the aperture 14 on the opposite side of the side wall, and the bolt 16 is inserted therein and screwed into locked position. 75

From the foregoing, it will be immediately apparent that I provide an easily adjustable flange for the overflow connection which, after adjustment, may be locked in adjusted position, said flange having frictional contact with the elbow 4. 80

The rearwardly extending beveled element 11 of the flange may engage either the inside or outside of the elbow. The bolt 16 is ordinarily termed a chain-stay, and has a ring 18 adapted to be connected to a chain carrying a stopper. 85

Of necessity, the joint between the wall of the bath tub and the enlarged head 4 must be tight and leak-proof since when the 90

tub is overfilled, the water must pass through the drain 15 and overflow pipe 3.

In Figure 2 I have illustrated one form of the invention in which the metal surface 5 of the flange is adapted to contact the metal surface of the elbow.

In Figure 5 I have illustrated a slightly different form of locking connection between the flange and head 4. I have dispensed 10 with the flat surface 9 and flange 12 and have indicated a slightly different form of flange 8. A flexible washer 19 may be mounted on the outwardly curving face 20 of the head 4 adapted to form a flexible non-metallic seat, with which the metal flange is adapted to have frictional engagement. This flexible washer 19 may, of course, be mounted 15 on the inside or outside of the enlarged head 4, and is particularly designed to provide a flexible seat for the purpose of more effectively making a tight, leak-proof connection when the assembly is locked.

It will be instantly apparent that the flange is capable of maximum adjustment in 20 either direction to compensate for the different slopes on side walls of bath tubs, sinks, or the like.

The entire assembly is economical to manufacture, simple to install, and very certain 30 in operation.

I claim as my invention:

1. In combination with an element having an overflow aperture and overflow connection adjacent one side of said aperture, including an overflow drain pipe having an 35

enlarged head provided with an open face, a flange adapted to be adjustably interposed between said wall and the wall of said element, comprising a circular piece of metal having a central opening and provided with 40 a flat annular margin portion from the inner edge of which projects an annular portion having a curved surface inwardly towards said central opening adapted to have adjustable cooperative engagement with said head, and an annular lip projecting from 45 said curved annular portion adapted to direct overflow water into the overflow drain pipe.

2. In combination with an element having 50 an overflow aperture and overflow connection adjacent one side of said aperture, including an overflow drain pipe having an enlarged head provided with an open face, a flange adapted to be adjustably interposed 55 between said wall and the wall of said element, comprising a circular piece of metal having a central opening and provided with a flat annular margin portion from the inner edge of which projects an annular portion 60 having a curved surface inwardly toward said central opening adapted to have adjustable cooperative engagement with said head, an annular lip projecting from said curved annular portion adapted to direct overflow 65 water into the overflow drain pipe, and an annular flange on the outer edge of the flat annular marginal portion.

WALTER J. FROST.
